The following is a report on the business, present and working part of the same, concerning a description and the results of the new type of the printing machine, and the improvement in the printing machine, as far as known as the Dactylo-Matic, printing machine.

In all other respects it may answer. Be it known that Mr. George Hartley of the City of New York has invented certain improvements in the printing machine or Napier Machine (as the double Napier Printing Machine is) consisting of ① A pair of London wire Coat Buttons which improvements are applied to the single cylinder Machine, and I do hereby declare that the following is a full and exact description of the said machine and my improvements. Fig. 1. Is a plan or top view of the machine which being in its general principle the same with the Napier Machine does not require to be particularly described in this, however A. is the tank for water to be more particularly noticed, B. is a piece of iron to which the slides connected with the printing apparatus are attached, C. the gripper arms with its pins and the gripper jaws below the surface of the cylinder. Fig. 2. is a side view of the machine. A. are the tanks as in Fig. 1. B. is an end view of the grippers upon their arms as noticed in fig. 1. This machine has two cylinders each making an impression on the form at every third revolution and as in this respect, as well as in its general construction, the same improvements with the Napier Printing machine before adduced to, but it differs from this machine in the arrangement of that part which takes and transforms the sheets from the bank book to the form of type, by which they are printed and afterwards delivered in their proper places. It differs also in the addition of that part used for perfecting the sheet, and this machine requires. For the purpose of taking the sheet from the bank book and turning them upon the form of type, they have to be delivered.

100-100

and the type and afterwards closing and delivering them in their proper places. I attach to each of these two a kind of apparatus, some machinery as that used by the said Napier, in his well known single cylinder Printing Machine, for that purpose. That is to say an arbor and wheel which I have called the gripper arbor. The grippers being so fitted thereto that they may be moved by tightening screws on any part required. Now one end of the gripper arbor there is a pinion of about one inch and a quarter in diameter, fixed permanently and this takes into a wheel which I call the gripper wheel, of about four inches in diameter having on about one fifth of its circumference teeth which correspond with those on the pinion.

A roller of steel or of iron called the checker roller made of the same thickness as the gripper wheel is fixed into its face by a steel pin and is thus made to fall into cavities formed on the periphery of the wheel at suitable distances; thus serving the purpose of stopping and retaining the grippers in their proper places. Near the periphery of the above wheel and parallel to its axis is a pin with a projection on its end projecting one inch or more beyond the end of the cylinder. This in the single cylinder machine at every revolution of the cylinder comes in contact with segments or pieces of iron of suitable form fastened permanently near the end of the cylinder, and thus by acting on the above named friction rollers attached to the gripper wheel, causes the grippers to close and open at every revolution of the cylinder. But in order to adapt these to my machine, a concavity is formed on one end of the cylinder of sufficient depth to admit the gripper arbor and its appendage to be sunk below the face of the cylinder, so as to pass clear of the type on the bed as the form passes under the cylinder, and also to allow the gripper with their arbor, to make nearly half a revolution back from the position in which they hold the sheet to the cylinder. The concavity terminates at a little distance from one end of the cylinder so as to leave a arbor to receive the first of one end of the gripper arbor. The other end, on which the pin-

iron fastened having its bearing and turning in the arm of a wheel which is fitted to the end of the cylinder shaft and which is also secured by screws against the end of the cylinder, they being of equal diameter, one of the ends of the gripper wheel is fitted to and turns in one of the arms of this wheel & the other in one of the arms of the cylinder which stands about two inches withouts and leaves a suitable space for that purpose. The shaft roller and the spring are also attached to the above named wheel. To cause the grippers to act at every third resolution of the cylinder only I attach the segments a b c figures 4 & 5. to a plate of iron P of about one fourth of an inch thick - which is permanently fastened to the piece of iron X fig. 5 & 6. This piece of iron turns upon a bolt or pin at i i and consequently allowing the plate P to move backward and forward. The piece of iron P figs 5 & 6. is fitted to and turns on a joint in the piece X at c c. There is a groove or slot in the lower end of the piece P. thro' which a screw passes into the slide S. in which it is tightened whilst a sufficient space is left between the head of the screw and the slide to allow the piece P to move freely up and down. To this piece P is attached the friction roller d figs 5 & 6. which works in an eccentric groove represented by the dotted lines in the wheel R fig. 2. This wheel is driven by a pinion h. fastened on the end of the cylinder shaft and having just but one third of the number of teeth which there are upon the wheel R. The part g of the groove must be such portion of a circle as will by its action on the friction roller keep the plate P in a perpendicular position whilst the cylinder is making about five parts of a resolution, or for such a period as is required between the commencement of the action of the segments on the grippers until it has opened them, when the top of the plate P. to which the segment a b c are attached, falls back into a horizontal position in order that they may not act on the grippers again until the third resolution of the cylinder when it is again brought to a perpendicular position. The tapes or cords are connected by rollers & pulleys

and are tightened by weights as in the single cylinder machine. For the purpose of perfecting the slides and making a gutter in back work, I attach a piece of sheet iron or steel to one end of each cylinder. These pieces may be about one sixteenth of an inch thick, and cut in even with the face of the machine firmly to the cylinder their edges projecting about half an inch on its ends. I fastening about two thirds of the way round the cylinder, commencing about ten inches back from the gripper arbors. To that end of the gripper, or opposite to that on which the pinion is fastened, I also attach a small roller set off about three fourths of an inch from and parallel with the centre of the arbor. This roller is also set nearly half an inch clear of the end of the cylinder. At a suitable distance back of each cylinder and parallel therewith I place a piece of iron as represented at B in fig 1. These pieces are attached by screws at each end to the beams or pieces that support the back board. To these pieces are fitted slides perpendicular to the face of the back board. They may be from twelve to fifteen inches apart and at equal distances from each end to these slides are fitted pieces of metal of such form as may be deemed most convenient for setting and gathering the prints, which are so attached as to project up through the back board.

Between the above slides and the cylinders at a distance of from four to six inches from the slides, there is a rod of iron which turns freely on its journals; to this rod two arms are fastened which extend back as far as the above slides and are connected by a link to the pieces fitted to the slides. One end of this rod is fastened, as shown at A in figs 1, 8, 2. The end of which is tipped by the eccentric roller on the end of the gripper arbor, whenever the gripper closes and is kept up in this place for the proper time by a small roller fitted to the end of the lever which is next to the cylinder and which lies on the sheet of steel or iron placed upon and projecting from the end of the cylinder. In the rotation of this iron there are small steel points fastened to the cloth on the face of the cylinder, and the end of the lever is raised so as not to be acted upon by the eccentric.

177
on the end of the gripper-arms. The sheet of paper is laid on the
horizontal with the edge a little over the centre of the cylinder and
at the first time the grippers catch the sheet and move it to the
end of the paper and the cylinder. The tips facing the points, thus the
paper which is caused between the cylinder and form and prints on
one side. When the second end is to be printed the lever is let down
and the sheet rests on the points projecting through the board which
move so as to correspond with the holes made in the sheet by the
points, on the face of the cylinder and at the moment the grippers
catch the sheet the points are withdrawn from it by the operation of
the eccentric fixed upon the end of the gripper-arms which acting
with the before described lever raises the end of it until the roller attached
to the side of it lies on the projecting sheet now resting on the
end of the cylinder. When the printing roller runs off from the end
of the sheet metal the lever is brought down by the action of a spiral
spring attached to the end on which the lever is placed. During the
next two revolutions of the cylinder the projecting sheet metal on
the end of the cylinder passes over the roller on the side of the lever.

What I claim as new and for which I ask a Patent, is the ma-
chinery herein described as the application of the above described grippers
to a printing machine, the cylinder of which makes those revolutions
to one impression, whether the apparatus by which they are acted upon
is constructed exactly in the manner described, or in any other op-
erating upon the same principle and producing an similar result.

I also claim the particular mode herein described of with-
drawing the apparatus which acts upon the grippers, not only
making more but also three printing only two revolutions
to each impression. I also claim the application of the eccen-
tric attached to the end of the gripper arms for the purpose of
withdrawing the points from the sheet, as applicable to the single cylinder
as well as the double cylinder Printing Machine.
